UNITED STATES PATENT OFFICE.

GEORGE W. PRISBREY, OF ST. GEORGE, UTAH, ASSIGNOR OF ONE-THIRD TO GRANT PRISBREY, OF ST. GEORGE, UTAH.

ARTIFICIAL LEG.

1,350,518.

Specification of Letters Patent. Patented Aug. 24, 1920.

Application filed August 1, 1919. Serial No. 314,739.

To all whom it may concern:

Be it known that I, GEORGE W. PRISBREY, a citizen of the United States, residing at St. George, in the county of Washington and State of Utah, have invented certain new and useful Improvements in Artificial Legs; and I do declare the following to be a full, clear, and exact description of the invention, such as will enable others skilled in the art to which it appertains to make and use the same.

This invention relates to artificial legs.

One object of the invention is to provide an improved ankle joint and improved securing means for uniting this joint with the foot and leg sections.

Another object of the invention is to provide an improved toe joint and improved securing means for uniting this toe joint with the foot and toe sections.

Another object is to provide improved knee joints and their connections.

Other objects and advantages may become apparent to persons who read the following details of description in connection with the accompanying drawings in which:—

Figure 1 is a side elevation of my improved artificial leg.

Fig. 2 is a front elevation of the same.

Fig. 3 is a vertical sectional view of the foot and the lower portion of the adjacent leg section, the section of this view being taken along the line 3—3 of Figs. 4 and 5.

Fig. 4 is a horizontal sectional view, the section being taken substantially along the line 4—4 of Fig. 3.

Fig. 5 is a vertical sectional view, the section being taken substantially along the line 5—5 of Fig. 3, the ankle joints and certain of its attaching elements being shown in full elevation.

Fig. 6 is a sectional view somewhat similar to Fig. 5, but the main portions of the ankle joint and certain of its attaching elements being shown in section.

Fig. 7 is an elevation illustrating the ankle joint and its leg-attaching elements detached from the other members of the leg and foot.

Fig. 8 is a detail sectional view illustrating the main elements of the toe joint, the section being taken along the line 8—8 of Fig. 10.

Fig. 9 is a side elevation illustrating the

toe section, toe joint and the attaching stud 55 of the latter.

Fig. 10 is a top plan view of the structure shown in Fig. 9.

Fig. 11 is a side elevation of one of the knee joints.

Fig. 12 is a front elevation of the knee joint shown in Fig. 11.

Fig. 13 is a vertical sectional view of the knee joint, the section being taken along the line 13—13 of Fig. 11.

Fig. 14 is a perspective view illustrating a group of knee joint elements separated from one another.

Referring to the drawings in detail, in which similar reference characters correspond with similar parts throughout the several views the device comprises broadly a stump socket 15, a leg section 16, a foot section 17, a toe section 18 and joints connecting the several members 15 to 18 inclusive. The stump socket is provided with a substantially inverted U-shaped strap or flexible element 19 and a flexible loop 20, these elements 19 and 20 being attachable to a belt or other supporting means in any appropriate way. A T-shaped bar 21 has its head and vertical stem secured to one side of the stump socket, and a similar bar 21 is similarly secured to the opposite side of the stump socket, rivets or other securing means being employed for uniting the stump socket with the bars 21. An inverted T-shaped bar 22 has its head and stem embedded in one side of the leg section 16 and secured by rivets or other suitable means, 90 and a similar bar 22 is similarly secured to the opposite side of the leg section. The bars 22 extend upward from the leg section 16 and are pivotally connected to the depending ends of the bars 21 in a manner to form knee joints, the details of construction of these knee joints being as follows:

Referring to Figs. 11 to 14, it will be seen that the lower end of each bar 21 is formed with oppositely extending bosses 23, the upper end of each bar 22 being formed with a recess or cavity 24 to receive one of these bosses, and a keeper 25 being formed with a recess 26 to receive the other one of this pair of bosses 23. Each cavity 24 and 26 is sufficiently large to receive a washer 27, and these washers surround the bosses 23 and fill the space between the bosses and

the annular casings of the cavity. The washers 27 may be formed of leather or any tough and pliable material, so that the knee joints (of which they are elements) are somewhat yieldable transversely of their axis. In other words, these washers cushion the knee joints to prevent them from rattling, and also serve as means for absorbing lubrication and applying such lubrication to the bosses 23 and adjacent working parts. Each bar 22 is formed with a groove 28 which receives a rib 29 of the contiguous keeper 25, the groove 28 and rib 29 being preferably arcuate so that these elements may be formed by the same rotary tool that forms the cavities 24; that is, the cavities may be bored or counter-sunk by means of a rotary tool having a lateral extension which forms the groove 28 or rib 29 simultaneously with the forming of the cavity. A screw 30 may be provided to extend through an aperture 31 of each keeper 25 and engaged with a screw threaded aperture 32 of one of the bars 22. Moreover, each keeper 25 may be provided with an aperture 33 which receives a stud 34 of the contiguous bar 22. It will be seen, therefore, that the elements 29, 31 and 33 of each member 25 coöperate with the corresponding elements 28, 32 and 34 of each bar 22 so as to removably secure a keeper 25 to one of the bars 22 in such relation that the maximum degree of rigidity and accurate positioning of these assembled parts is assured.

Referring now more particularly to Figs. 3 to 7 inclusive, it will be seen that the leg section 16 has a recessed lower end, the recess thereof being of a size and shape to conform to the contour of a bearing plate 35 and the socket members 36 which are united with this plate. This lower recess communicates with an upper recess or cavity 37 through the medium of vertical bores or passages which receive screws or bolts 38. The lower ends of the bolts 38 are united with the upper ends of the sockets 36, and the upper ends of the bolts 38 are provided with nuts 39 which coöperate with the bolts to hold the plate 35 and sockets 36 in the lower recess of the leg member 16. Therefore, the elements 35 and 36 are rigidly united with the leg section 16.

The plate 35 is provided with an approximately cylindrical groove 40 which extends forward and rearward, and this plate is also apertured and screw threaded to receive a screw 41. An approximately cylindrical supporting element 42 is formed on top of a rib which extends upward from a tubular element or casing 43, and a groove 44 extends laterally across the supporting element 42 and receives the lower end of the screw 41 so as to prevent longitudinal movement of the bearing element 42 in its

seat or bearing 40. The member 42-43 constitutes a joint member which is pivotally connected to the foot member by means of the element 43, and connected to the leg member by means of the element 42, 70 the axes of these elements 42 and 43 crossing one another. The plate 35 may oscillate or have rotary movement laterally of the supporting or bearing element 42, thereby permitting a limited lateral oscillating 75 movement of the foot section with relation to the leg section, as will more clearly appear hereinafter. Springs 44 have their upper ends seated in the sockets 36 and their lower ends seated against the upper 80 surface of casing 43, pins 45 being provided to retain the springs in their proper position. These springs press equally at equal distances at opposite sides of the bearing member 42, and constitute balancing 85 means to hold the plate 35 in its substantially horizontal position. Recesses or clearance spaces 46 are provided on opposite sides of the ankle portions of the leg, and either of the springs may be compressed 90 while the other expands by its inherent springiness, and therefore, the foot section has a limited and somewhat resisted lateral movement about the pivotal connection 40-42. 95

The casing 43 is supported by means of a pair of brackets or supports 77 which are substantially L-shaped, each of these supports comprising a horizontal apertured lower end which extends under the foot and 100 is secured thereto by screws or other appropriate means. The upper ends of the supports 77 extend upward from opposite sides of the foot section and are provided with flanges 78 which extend over a depressed 105 portion or laterally extending groove 43' in which the casing 43 is mounted to rotate.

The flanges 78 provide bearings in which the ends of the cylindrical casing 43 are journaled and absorbent packings may be 110 provided at the ends of the casing 43 to lubricate the bearings or flanges 78.

For the purpose of causing rotary movement of the barrel or casing 43, a torsional spring 79 is disposed within the casing 43 115 and has one end engaged with the casing, the other end of this spring being engaged with a lug 80 which is united with the tubular supporting and adjusting member 81. The ends of the member 81 are supported 120 in recesses or seats provided in the inner faces or members 77. A screw 82 extends through the bearings 77 and tube 81, and one end of the screw 82 has threaded engagement with one of the bearings 77. 125 Therefore, by tightening the screw 82, the tube 81 is clamped between the bearings 77 and rigidly united therewith, the elements 81 and 82 forming a bridge across the foot section, but when the screw 82 is loosened, 130

the tube 81 may be turned so as to regulate the tension of the spring 79. Therefore, the spring may be tensioned or adjusted so that the foot offers a greater or less resistance to being rotated or oscillated about its pivot or ankle joint.

The barrel or casing 43 is formed with a slot 83 through which a pin or stud 84 extends from the tube 81. The inner end of the pin 84 is preferably engaged with one of several screw threaded apertures (not shown), and by changing the screw 84 from one to another of such apertures, the spring 79 may be held under different degrees of tension, it being understood that the slot 83 limits movement of the pin 84 in one direction but permits it to move in the opposite direction so that the tube 81 may be turned for effecting a still greater degree of tension 20 of the spring 79.

The toe section is preferably formed of primarily separate superposed plates of leather or other light and somewhat flexible material, and any appropriate securing means may be employed as indicated at 85, for securing the upper and lower portions or plates of the toe section in unison. A substantially U-shaped wire or rod 86 has its middle portion seated 30 and clamped between the upper and lower portions of the toe section, the ends of this member 86 extending rearwardly from the toe section and being engaged with a shaft 87 so as to support the latter in horizontal 35 position. Disks 88 are rigidly united with the shaft 87, and these disks constitute bearings for the ends of a barrel or casing 89 which is rigidly united with the foot section 17 by means of a stud or bolt 90 and a 40 nut 91, a recess or cavity 92 being formed in the foot section for receiving the nut. A spring 93 has one end engaged with one of the disks 88 and has its other end engaged with the barrel or casing 89 so as to effect 45 rotary relative movement of the foot and toe sections through the medium of the casing 89 and shaft 87.

Referring again to Fig. 14 it will be seen that shoulders 21', 22' and 25' are formed 50 on the members 21, 22 and 25 respectively, and the shoulders 22' and 25' unitedly coact with the shoulders 21' for limiting forward and rearward the rotary movements of the knee joint.

55 Although I have described this embodiment of my invention very specifically, it is not intended to limit this invention to these exact details of construction and arrangement, but changes may be made within the 60 scope of the inventive ideas as implied and claimed.

What I claim as my invention is:

1. In an artificial leg, a leg section, a foot section, a joint member pivotally connected 65 to the leg section and pivotally connected to

the foot section, and elastic means to swing the leg section and foot section about their pivoted connections, the axes of said pivotal connections crossing one another to permit different angular movements of the leg section and foot section relative to said joint member.

2. In an artificial leg, a leg section, a foot section, bearings extending up from opposite sides of the foot section, a casing rotatably supported by said bearings and having a pivotal leg-supporting element on and extending up from its outer surface, springs on opposite sides of said leg-supporting element and being correlated with the casing for balancing the leg portion on said leg-supporting element, and means including a spring within the casing to effect rotary movement of said casing.

3. In an artificial leg, a leg section, a foot section, bearings extending up from opposite sides of the foot section and comprising annular flanges, a cylindrical casing having primarily open ends closed by said bearings and rotatably seated in said annular flanges, said leg-section being supported by said casing, a bridge extending through said casing and rigidly connecting said bearings to one another, and a torsional spring coiled around said bridge and being engaged with the latter and with said casing so as to effect rotary movement of the casing relative to said bearings.

4. In an artificial leg, a leg section, a foot section, bearings extending up from opposite sides of the foot section and comprising annular flanges, a cylindrical casing having primarily open ends closed by said bearings and rotatably seated in said annular flanges, said leg-section being supported by said casing, a tubular bridge member having its ends abutting against the inwardly facing surfaces of said bearings, a screw extending through said tubular bridge member and coacting therewith to rigidly unite the said bearings, and a torsional spring surrounding said tubular bridge member and being engaged with the latter and with said casing for effecting rotary movement of the casing relative to said bearings.

5. In an artificial leg, the combination with a leg-section comprising a body having a recessed lower end, a bearing plate fitted in the said lower end, spring receiving sockets united with and extending up from said plate into recesses of said body, and screw-threaded fasteners united with and extending up from said sockets into engagement with said body, of a foot section, an ankle joint structure connected to the foot section and to the said bearing plate, and springs having their upper ends in said sockets and their lower ends engaging with said ankle joint structure.

6. In an artificial leg, the combination of

a foot section, a pair of leg-bearing brackets each formed with a horizontal lower portion and with an upright bearing portion, said horizontal portions extending under and secured to the lower side of the foot section, a bridge uniting the upper ends of said brackets, an ankle-joint member supported by said brackets and adapted to support a leg-section, and a spring surrounding and connected to said bridge and being engaged with said ankle joint member so as to control the latter.

7. In an artificial leg, an ankle joint member comprising an upstanding rib having an approximately cylindrical top formed with a lateral groove, a bearing plate adapted to be secured to a leg member and having an approximately cylindrical bearing recess in which said approximately cylindrical top is seated for rotary movement, and means extending from said bearing plate into said lateral groove to prevent longitudinal movement of said rib relative to said plate.

8. In an artificial leg, a foot-section, a leg-section, bearings secured to and extending up from opposite sides of the foot section, an ankle joint member supported by said bearings and supporting said leg section, a spring disposed between said bearings and engaged with said ankle joint member and being inherently operable to impart rotary movement to the latter, and means carried by and coacting with said bearings for regulating the tension of said spring.

9. In a joint, a bar adapted to be secured to an artificial leg section and provided with a head having bosses extending laterally from its sides, a bar adapted to be secured to another leg section and having a hollow head forming one section of a bearing housing, a keeper releasably connected with the second bar and having a hollow head forming the second section of the bearing housing, the head of the first bar extending into the bearing housing with its bosses extending transversely therein, and nonmetallic washers fitting within the bearing housing against the sides of the head of the first bar and about said bosses and adapted to absorb a lubricant.

10. In an artificial foot, a foot section, a toe section, a casing secured to the foot section, a shaft secured to said toe section and extending through said casing, and a spring in the casing and having one end fixed with relation to said shaft and its other end fixed with relation to said casing and being effective to cause a rotary relative movement of the shaft and casing.

11. In an artificial foot, a foot section, a toe section, a shaft secured to said toe section, a pair of disks secured respectively on the end portions of said shaft, a casing enclosing the disks and rotatably seated thereon, but held against axial movement relative thereto and a spring coiled around the part of the shaft between said disks and having one end secured to one of said disks, the other end of said spring being engaged with said casing to effect its rotary movement relative to said shaft.

12. In an artificial foot, a foot section, a toe section composed of superposed primarily separate portions, a U-shaped rod having its middle portion seated between said superposed portions and having its ends extending rearward, a shaft carried by the rearwardly extending ends of said rod, means pivotally connecting said shaft to said foot section, and a spring connecting said means with said shaft and being effective to cause rotary relative movement of the foot and toe sections.

13. In a knee joint, a bar adapted to be secured to an artificial leg section and comprising an end portion having oppositely extending bosses, a bar adapted to be secured to another leg section and comprising a cavity in which one of said bosses is seated, a keeper having a cavity in which the other one of said bosses is seated, said keeper having a rib extending laterally thereacross, the second said bar having a groove extending thereacross and having said rib fitted therein, and means coacting with said rib and groove for removably but otherwise immovably securing the keeper on the second said bar.

In testimony whereof I have hereunto set my hand.

GEORGE W. PRISBREY.
